(57) **CLAIM**

The ornamental design for a golf alignment training guide, as shown and described.

DESCRIPTION

FIG. 1 is a perspective view of a golf alignment training guide, in accordance with the ornamental design, illustrated showing golf tees, ball and golf club in phantom as would be seen in actual use;

FIG. 2 is a top exterior perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

The broken lines showing of the tee and golf ball, the golf club, and the tee holding and pivoting the guide into the ground are for illustrative purposes only and forms no part of the claimed design.
